CONTAINER

Robert J. Crawford, Locust, N. J., assignor to
 American Can Company, New York, N. Y., a
 corporation of New Jersey

Application December 12, 1944, Serial No. 567,830

2 Claims. (Cl. 220—40)

1

This invention relates to a container having a tubular body and a metal ring member secured thereto in an end seam, the ring member having an inwardly and upwardly extended annulus terminating in an edge defining the mouth of the container and has particular reference to a plurality of spaced transverse deformations in the annulus and spaced angular locking sections in the annulus for the reception of a metal cover which has a plurality of locking lugs cooperating with the angular locking sections of the annulus during a slight rotation of the cover for locking the cover in place thereon.

An object of the invention is the provision of a container having preferably a cylindrical container body with a metal ring secured to the top end thereof, the ring having an inwardly and upwardly extended annulus terminating in an edge and provided with a plurality of spaced transverse shallow and deep deformations alternately arranged to define spaced angular edge locking sections which are adapted to receive locking lugs of a metal cover, the cover being locked in place by a slight rotation relative to the body.

Another object of the invention is the provision in a container of the character described, of a frangible sealing disc preferably secured to the top end of the container body by the metal ring, the metal cover having an annular wall overlying the metal ring with a countersunk panel or plug extending into the mouth of the container when the cover is applied thereto, the cover also having an outside depending skirt preferably terminating in a curled edge with corrugations in the periphery of the skirt to provide a hand grip for the application and removal of the cover.

Numerous other objects and advantages of the invention will be apparent as it is better understood from the following description, which, taken in connection with the accompanying drawings, discloses a preferred embodiment thereof.

Referring to the drawing:

Figure 1 is a perspective view of a container and cover disclosing a preferred embodiment of the present invention;

Fig. 2 is a top plan view of the container shown in Fig. 1 with the cover removed;

Fig. 3 is a vertical sectional view of the upper part of the container shown in Fig. 1 taken substantially along the line 3—3 in that figure;

Fig. 4 is a fragmentary view similar to Fig. 3 showing the cover in a different position;

Fig. 5 is a view similar to Fig. 3 and showing the cover in locked position on the container; and

Fig. 6 is a vertical sectional view of the upper portion of the container taken along the section line 6—6 in Fig. 2 and showing an angular locking section in the annulus of the upper metal ring member.

2

As a preferred embodiment of the invention the drawings disclose a container 11, which includes a tubular body 12 made of fibre, metal or other suitable material having a metallic end secured to the bottom end of the body in a suitable end seam (Fig. 1). The top end of the body 12 is closed in part by a temporary sealing disc 14, made of cellophane, paper or other suitable frangible material which is adapted to be cut out to gain access to the container interior.

The frangible disc 14 may be held in place by an annular depending wall 15 of a metal ring 16 which is secured to the upper end of the body in a suitable end seam 17 (Figs. 3 to 6). The depending ring wall 15 extends inwardly and downwardly as an inclined circular wall 18, thence inwardly and upwardly to constitute an inclined upwardly extending annular wall 22, thereby providing a channel 23 therebetween. Wall 22 terminates in an upper inner periphery which is preferably formed with a rounded or hemmed edge preferably disposed in the same transverse plane as the end seam 17. Obviously this edge may also remain a raw edge. The ring member wall 22 together with its edge will be hereinafter referred to as an annulus 24 defining the mouth of the container (see also Fig. 2).

An otherwise regular contour of the annulus 24 is altered at spaced intervals around its inner edge by depressing the metal at an angle to the horizontal between two spaced transverse shallow and deep deformations, depressions or indentations. Each shallow deformation with its associated deep deformation isolates or defines a depressed space in the annulus 24 setting it off as an inclined locking section 25 (Figs. 2 and 6).

Four locking sections 25 are shown in the drawings. These may be more or less, depending upon the diameter of the container. Each section may be said to start at a lead-in end in the shallow deformation or indentation (as indicated by the numeral 26) and to terminate at the lower or opposite end in the deep depression (as indicated by the numeral 27). The edge of the locking section at the shallow deformation 26 is pressed into depending cover hurdle element 32 (see Fig. 6) and at the deep depression 27 into a depending cover stop element 33. These snaps and stops facilitate the application of a removable cover 34 for the container and provide for the proper locking of the cover as will be described hereinafter.

The edge of each locking section 25 is arcuate but is not concentric with the inner unpressed edge of the annulus 24. This locking section edge is drawn inwardly to a smaller diameter. The making of the shallow depression 26 draws that end of the section edge inwardly a slight amount and the making of the deep depression 27 draws

the terminal end still closer to the center of the ring as best seen in Fig. 2. This construction makes possible the locking of the cover 34 as will be clearly understood in the later consideration of the application of the cover to the container.

The cover 34 has an annular horizontal wall section 35 which is adapted to engage the upper surface of the end seam 17, with or without a sealing gasket interposed therebetween and also to rest upon or bridge the unpressed portions of the annulus 24 when the cover is applied to the container. This cover is formed with a countersunk central panel 36 disposed at the inner end of a depending surrounding inner cover wall 37 which extends down into the mouth of the container (Figs 1, 3, 4 and 5) inwardly of the annular cover wall 35. The depending wall 37 has a plurality of equally spaced outwardly extending locking lugs 38. There are four such lugs as shown in the drawings and these constitute the holding or locking means for the cover.

The cover 34 also has an outer depending skirt 42 extending from the annular wall section 35. This depending skirt projects down over and fully embraces the end seam 17 when the cover is in closed position on the container. The skirt 42 terminates at its lower end in a preferably outwardly curled rounded or hemmed edge 43 (Figs. 1 and 5).

In applying the cover the locking lugs 38 of the cover are positioned directly over and just inside of the unpressed portions of the annulus 24. The cover is then lowered in place, the countersunk panel 36 passing into the mouth of the container. The distance between opposite lugs 38 is less than the diametric distance between opposed unpressed portions of the annulus so that the cover easily drops down with its horizontal wall 35 seated on the end seam 17 (Fig. 4).

The cover cannot be put on in the wrong position since the diametric distance between opposite inclined locking sections 25 of the ring is less than the over-all distance between opposed locking lugs 38. The locking of the cover takes place by a partial rotation relative to the container. In such rotation each lug 38 first snaps under the associated cover hurdle element 32 and then passes under the inwardly inclined locking section or thread until the cover is tightly locked in seating position on the seam 17 of the container, with or without the aid of a sealing gasket.

This partial rotation of the cover must occur in the proper direction for should an attempt be made to turn in the wrong direction each stop element 33 on ring 24 would act as a barrier for the associated cover lug 38 and the lug would remain in the region of the unpressed edge portion of the annulus 24 and would not engage the inclined locking section 25 to lock the cover in closed position on the container. After the cover has been rotated sufficiently to pass a lug 38 under its associated cover hurdle element 32, the latter acting as a barrier will prevent accidental reverse rotation which might otherwise result in loss of the cover.

In order to facilitate the rotation of the cover during its application onto the container and during its removal therefrom, corrugations or knurling 44 are formed in the periphery of the cover skirt 42 (Figs. 1, 3, 4 and 5). These corrugations thus assure a firm hand grip on the cover.

It is thought that the invention and many of its attendant advantages will be understood from the foregoing description, and it will be apparent that various changes may be made in the form, construction and arrangement of the parts with-

out departing from the spirit and scope of the invention or sacrificing all of its material advantages, the form hereinbefore described being merely a preferred embodiment thereof.

5 I claim:

1. A dispensing container, comprising in combination, a tubular body, said body at the dispensing end thereof terminating in an annular cover seating member, said annular member extending inwardly toward the axis of said body and including an annular channel portion and as a continuation of said channel portion an upwardly extending annular wall terminating in a continuous edge which defines the dispensing mouth of the container, spaced portions of said edge being depressed to provide cover locking sections leaving intermediate undepressed cover receiving sections, said cover locking sections being inclined to the horizontal and radially spaced from said body axis a lesser distance than said undepressed cover receiving sections, a cover for the container having a central plug portion adapted to fit within said mouth and having an outwardly extending flange, said plug comprising an annular depending countersunk wall, a central panel and a series of spaced locking lugs, said cover locking lugs passing through said undepressed cover receiving sections when the cover is applied and coacting with said cover locking sections when said cover is rotated to lock said cover and said member together, said flange overlying said member in seating position.

2. A dispensing container, comprising in combination, a tubular body, a cover seating member provided at one end of said body, said cover seating member having a channel portion concentric with the axis of said container, and having inwardly of said channel portion and as a continuation thereof an inwardly and upwardly inclined annular wall terminating in a continuous edge defining the mouth of the container, spaced portions of said wall being concentric with said channel portion and spaced intermediate portions of said wall being depressed in eccentric relationship to said concentric portions to provide inclined spaced cover locking sections between said concentric portions, a cover having a plug portion snugly fitting within the mouth of the container, said cover having a plurality of locking lugs formed in said plug portion respectively insertable through said concentric wall portions, said cover locking lugs coacting with said depressed locking sections of said seating member to lock together said container and said cover when the cover is rotated.
